UNITED STATES PATENT OFFICE.

JOHN A. SIMPSON, OF EAST CAMBRIDGE, MASSACHUSETTS, ASSIGNOR TO
HOWARD M. SAWYER AND CHARLES H. SAWYER, OF SAME PLACE.

LAMP-SUPPORT FOR MINERS' HATS.

SPECIFICATION forming part of Letters Patent No. 511,365, dated December 26, 1893.

Application filed March 8, 1893. Serial No. 466,593. (No model.)

To all whom it may concern:

Be it known that I, JOHN A. SIMPSON, of East Cambridge, in the county of Middlesex and State of Massachusetts, have invented a new and useful Improvement in Lamp-Supports for Miners' Hats, of which the following, taken in connection with the accompanying drawings, is a specification.

My invention relates to lamp supports for miners' hats, and it consists in certain novel features of construction, arrangement and combination of parts which will be readily understood by reference to the description of the accompanying drawings and to the claim 15 hereinafter contained and in which my invention is clearly pointed out.

Figure 1 of the drawings is a side elevation of my improved lamp support as it appears attached to a hat, and the lamp supported thereon, said hat being represented in outline by dotted lines. Fig. 2 is a front elevation of my improved lamp support. Fig. 3 is a sectional elevation of the same the cutting plane being on line $x-x$ on Fig. 2. Fig. 4 is a 25 front elevation of a base plate made partly of metal and partly of leather. Fig. 5 is a transverse section on line $y-y$, on Fig. 4. Fig. 6 is a perspective view of the bracket for supporting the lamp, and Fig. 7 is a horizontal section through a portion of the bracket on line $v-v$, on Fig. 3.

In the drawings A is the base plate of the lamp support which may be made entirely of sheet metal as shown in Figs. 1, 2 and 3, 35 or of metal and leather as shown in Figs. 4 and 5.

The base plate A has formed therein or secured thereto two parallel sockets a to receive the two parallel shanks b of the bracket 40 B as shown in Figs. 2, 3, 4 and 5. When the base plate is made of a single piece of metal the sockets to receive the bracket are formed by cutting six short horizontal slits through said metal in two rows of three stamping or swaging 45 the metal between, above and below said slip so as to throw portions of said metal outward or beyond the front surface of said plate and other portions toward the rear as shown in Figs. 2 and 3.

50 In some cases it is desirable to have the base plate more flexible than it can be if

made entirely of metal, in which case I make the base plate of leather and secure thereto a metal socket plate A' formed by doubling a strip of thin sheet metal upon itself with a 55 loop or socket at each fold as shown in Figs. 4 and 5.

The bracket B is composed of the bar or rod c having formed therein the annular groove c' , and the shanks b , b , formed from a 60 single piece of wire which is passed through said rod c and bent to the shape indicated in Figs. 3 and 6, with two side horizontal portions b' , b' , fitting into the radial end grooves d , d , formed in the rod or bar c as shown in 65 Figs. 6 and 7.

The base plate A is secured to the hat in its appropriate position by sewing through the holes e , e , at its corners or by riveting as may be preferred, and when the bracket B is 70 detached therefrom the hats may be packed one within another in packages of a dozen or any other desired number for transportation, while a like number of the brackets B may be conveniently packed within the crown of 75 the outer hat of the package. This is a great advantage to the manufacturer, especially when applied to stiff or water proof hats.

The lamp C is of ordinary construction and is provided with the hook h by which it is 80 suspended from the bracket B in the ordinary way.

What I claim as new, and desire to secure by Letters Patent of the United States, is—

The combination with a miner's hat, of the 85 base plate A provided with two sockets a formed by cutting slits in said plate swaging contiguous portions of said plate in opposite directions; and the detachable bracket B provided with the parallel shanks b and the 90 bar or rod c having the annular groove c' to receive the lamp hook substantially as described.

In testimony whereof I have signed my name to this specification, in the presence of 95 two subscribing witnesses, on this 15th day of March, A. D. 1893.

JOHN A. SIMPSON.
